DIFFUSER OF VAPOROUS LIQUIDS

Allen T. Roeh, Cincinnati, Ohio

Application June 11, 1937, Serial No. 147,701

5 Claims. (Cl. 299—23)

This invention relates to air purifiers and more particularly to a diffuser of vaporous liquids which is adapted to be utilized to purify the air of toilets and similar places.

5 The principal object of my invention is to provide an air purifier which is adapted to be conveniently and readily serviced and cleaned.

Another object of my invention is to provide 10 an air purifier comprising a diffusion apparatus for volatile liquids and having a readily removable wick-base and holder therein.

A further object of my invention is to provide 15 an air purifier having superior diffusion characteristics for the diffusion of a volatile, oxidizing, and purifying liquid therefrom.

In providing wick bases and holders for air purifying apparatus, it has heretofore been the practice to utilize a metallic cup having an interior metal cylinder of smaller diameter than 20 the cup, inserted therein, a wick of woven material such as wool was then inserted around the interior metal cylinder and into the space formed for its reception between the interior of the cup and the exterior wall of the cylinder. The wick 25 was then saturated by suitable means with a volatile liquid. In the operation of such a wick holder and base, diffusion of the volatile liquid from the interior surface of the wick was practically prevented by its proximity to the interior surface 30 of the metal cylinder. Furthermore, the wicks had a tendency to stick to the metal cylinder and they were difficult to remove when it was desired to clean the interior surface of the metallic cup and the exterior surface of the metallic cylinder.

35 According to the present invention, the above difficulties and disadvantages have been obviated by providing a device in the base of the air purifier which permits the diffusion of liquid from the interior surface of the wick and which is readily disassembled for cleaning and servicing.

40 With the above and other objects in view, the invention consists in general of certain novel details of construction and combination of parts hereinafter fully described, and illustrated in the 45 accompanying drawing.

These and other objects are attained by the means described herein and disclosed in the accompanying drawing, in which:

Fig. 1 is a plan view of a device embodying my 50 invention, having walls cut away to show the relation of parts.

Fig. 2 is a top view of a wick holder forming a detail of the invention.

Fig. 3 is a fragmental side view taken on the 55 line 2—2 of Fig. 2.

Fig. 4 is a cross-sectional plan view showing the relation of a wick to a plurality of wire supports in one form of the invention.

Fig. 5 is a view similar to Fig. 4 showing the relation of a wick to four wire supports therefor 5 and of a modified form.

In the embodiment of my invention shown in the present drawing, there is provided a foraminous hollow shell or housing, comprising an elongated annular container 1 having a base or bottom 2 and a hinged top 3. A plurality of apertures 4 are provided in the lower portion of the container 1 and in the top, not shown.

An annular removable wick base cup 5, preferably made of molded material such as "Bakelite", 15 is provided for insertion into the base of the container. The cup 5 is provided with upwardly extending wall or side portion 6 and an elevated circular platform 7 is provided within the cup 5. Depending legs or lugs 8 are provided on the 20 bottom surface of cup 5. A split ring prong holder of spring metal may be inserted around the edges of the circular platform 7, and the split ring 9 is provided with a plurality of upwardly extending prongs 10 which are adapted to hold a wick 11 of woven material and to support the shoulders of an inverted bottle 12, containing a liquid 13. The bottle 12 is provided with a screw threaded neck portion 14, containing a check valve (not shown) having a wire release pin 15 extending 30 from said check valve.

In operating my improved air purifier, the bottle 12 is filled with a suitable volatile liquid and the check valve is inserted in the neck thereof. The split ring prong holder 9 is then inserted 35 around the circular platform 7 of the cup 5 and a suitable wick 11 is then inserted over the prongs 10 as shown in Fig. 5, or the wick may be interwoven between the prongs as is clearly shown in Fig. 4. The cup 5 having the wick assembled 40 thereon is then inserted into the base of the container 1. The inverted bottle containing liquid is then inserted into the container 1 so that it is supported by the heads of the prongs 10. The wire release pin 15 is at such time pushed upward 45 into the bottle 12, by contact with the platform 7, releasing the fluid and permitting it to flow into the cup 5, thereby thoroughly saturating the wick 11 by capillary action. The volatile fluid evaporates from the wick 11 and passes out of the 50 container 1 by way of apertures provided in the housing or shell.

The split spring ring 9, in its normal or unsprung condition, is of such diameter, that in order to position same around the central boss 55

or platform 7 of the reservoir, cup or receptacle 5, it is necessary to slightly expand or extend the ring 9, thus providing a substantial, rigid and frictional mounting of the ring upon the cup 5. The tension so applied to the ring, gives the ring a firm grip on the boss or platform 7. This arrangement permits ready attachment and detachment of the combined wick and bottle support 10 on the cup. Likewise, when the support 10 is detached from the cup, wicks may readily be detached from or applied over same by causing the split ring 9 to pass through the hollow center of the wick. In normal operation, the mouth of the inverted bottle 12 is beneath the upper edge of cup 5, thus providing for discharge of fluid from the bottle, controlled by the fluid level in the cup 5.

The lugs or legs 8 prevent formation of a vacuum between the base 2 and cup 5 which might prevent ready separation of the cup from the base 2.

From the above description of my improved air purifier, it will be apparent that I have provided a device which has improved diffusion capacity and which also may be readily assembled and disassembled.

The foregoing detailed description has been given for clearness of understanding only and no unnecessary limitation should be understood therefrom, but it should be construed as broadly as permissible in view of the prior art.

What is claimed is:

1. An air purifier of the kind described herein comprising an apertured container having a base portion and a hinged cap, a removable wick base cup adapted to rest upon the interior of the container base, said base cup having upwardly extending edges, and a circular elevated platform upon its upper surface and depending legs upon its lower surface, a split ring prong holder embracing said circular elevated platform and in frictional engagement therewith, said prong holder having a plurality of upwardly extending prongs for the reception of a wick thereon and to support the shoulders of an inverted bottle, a wick surrounding said prongs and extending into said base cup, an inverted bottle containing fluid within said container and supported upon said prongs, said bottle having a neck containing a valve and a release pin adapted to permit the flow of liquid through said bottle neck and into said base cup and wick.

2. An air purifier comprising a container having apertured side walls, a base, and an apertured hinged cap on the top of said container, a removable wick base cup adapted to rest upon the interior of the container base, said base cup having upwardly extending edges, and a circular elevated platform upon its upper surface and depending legs on its lower surface, a ring prong holder embracing said circular elevated platform and in frictional engagement therewith, said prong holder having a plurality of upwardly extending and outwardly bent prongs for the reception of a wick thereon and to support the shoulders of an inverted bottle, a wick interwoven with said prongs and extending into said base cup, and an inverted bottle containing fluid within said container and supported upon said prongs, and means on the neck of said bottle for controlling the passage of fluid therethrough.

3. A removable wick base and holder comprising a cup having upwardly extending edges, a circular elevated platform, said platform having in frictional engagement therewith a split ring prong holder having a plurality of upwardly extending prongs attached thereto.

4. A removable wick base and holder comprising a cup having upwardly extending edge portions, a circular elevated platform on the upper surface of said cup, a split ring prong holder embracing said platform and in frictional engagement therewith, said prong holder having a plurality of upwardly extending prongs attached thereto, and a wick of woven material extending over said prongs and into said cup.

5. In a device of the class described the combination of a foraminous housing, a non-metallic rigid cup supported in said housing, the cup having an upwardly extending boss formed on its bottom wall, a spring metal ring frictionally receiving and extending about said boss, a plurality of spaced supporting members carried by the ring, an annular wick supported in extended position by said supporting members, with the lower end of said wick disposed within said cup, and a supply reservoir open at its lower end only, disposed upon and supported by the upper portions of said supporting members, with the opening therein positioned in the cup and below the upper edge of the cup.

ALLEN T. ROOCH.
